UNITED STATES PATENT OFFICE

154,816

DESIGN FOR A HANDBAG OR SIMILAR ARTICLE

Jessica Smith Steck, Newtown, Conn.

Application September 23, 1948, Serial No. 148,723

Term of patent 3½ years

(Cl. D87—3)

To all whom it may concern:

Be it known that I, Jessica Smith Steck, a citizen of the United States of America, residing in Newtown, county of Fairfield, and State of Connecticut, have invented a new, original, and ornamental Design for a Handbag or Similar Article, of which the following is a specification, reference being had to the accompanying drawing, forming part thereof.

Fig. 1 is a perspective view of a handbag showing my new design, the opposite side of the handbag being substantially the same as that shown, and

Fig. 2 is a fragmentary perspective view on a reduced scale showing the back of one of the two similar pouch elements of the handbag.

I claim:

The ornamental design for a handbag or similar article, substantially as shown and described.

JESSICA SMITH STECK.
